UNITED STATES PATENT OFFICE.

FREDERICK M. HASENFUS, JR., OF PHILADELPHIA, PENNSYLVANIA.

COLLAR-BUTTON AND NECKTIE-FASTENER.

SPECIFICATION forming part of Letters Patent No. 678,663, dated July 16, 1901.

Application filed November 27, 1899. Serial No. 738,291. (No model.)

To all whom it may concern:

Be it known that I, FREDERICK M. HASENFUS, Jr., a citizen of the United States, residing in the city and county of Philadelphia, State of Pennsylvania, have invented a new and useful Improvement in Collar-Buttons and Necktie-Fasteners, which improvement is fully set forth in the following specification and accompanying drawings.

10 My invention consists of a collar-button and necktie-fastener, the same embodying a cap with openings or recesses therein and a cross-bar which is adapted to enter said cap and be interlocked with the same, the novel 15 features of said parts or members being pointed out in the claim that follows the specification.

Figure 1 represents a perspective view of a collar-button and necktie-fastener embodying my invention. Fig. 2 represents a view of the interior of one of the members thereof. Fig. 3 represents a partial elevation and partial section, the latter being on line xx , Fig. 2.

Similar letters of reference indicate corresponding parts in the figures.

Referring to the drawings, A designates a hollow cap or case having an open back and rim thereon with perforations, whereby it may be sewed or otherwise fastened to a necktie, such as B. In the head of said cap is the central opening C and aside of the same the openings D D, said opening C being of greater length than said openings D.

E designates a collar-button which is formed of the head F, the shank G, and the cross-bar H, the ends of the latter being provided with tongues J, which are turned inwardly toward the head F, it being noticed that said head F and cross-bar H are on opposite ends of said shank G.

The operation is as follows: The button is applied to the neckband of a shirt and has the collar adjusted thereon as usual, the cross-bar being on the outside portion of said band and collar being shown in dotted lines, Fig. 3. The necktie is now presented to the cap A so that the opening C registers with the cross-bar H and then receives said cross-head with the tongues thereon, the tongues also

50 entering said cap through said opening until they clear the outer wall of the cap, when the necktie has a half-turn imparted to it when the

tongues reach the side openings D and spring into the same, owing to the resiliency afforded by the portion of the necktie at the open back 55 of the cap, as will be hereinafter more fully described, and the pressure of the collar and neckband thus firmly connecting the tie with the collar-button and preventing rotation of the former. When, however, the cap is 60 pressed in, the tongues leave the openings D, and the tie may be rotated until the cross-bar and tongues register with the opening C, when the cap may be withdrawn from the button, and the tie is accordingly released from 65 the same.

It will be observed that the members of the two-part device are rigid in their nature and avoid the use of springs or parts that require to be contracted in order to be connected and 70 disconnected, and hence possess strength and durability and are of simple and inexpensive construction.

In order to prevent wearing action of the cross-bar H on the material of the necktie, 75 the interior of the cap A has a washer or rubber plate forming the guard K of suitable material within it, the same receiving the impact and contact of said cross-bar, the effect of which is the primary yielding of the washer 80 until the tongues J are fully within the cap, so the portion of the necktie extending across the open back of the cap being forced out by said washer creates pressure on said washer, and consequently on the cross-bar, 85 so that when the latter is properly turned the tongues spring into the openings D and are retained therein indirectly by the pressure of the portion of the necktie at the place indicated. 90

The rim or flange on the circumference of the side of the cap or back thereof forms a broad base, so that the cap lies flat on the tie without liability to cut the same or overturn, leaving the back of the cap entirely open for 95 the pressure of the tie against the loose guard-plate.

Having thus described my invention, what I claim as new, and desire to secure by Letters Patent, is—

A member consisting of a shank, a head, and a cross-bar with an inturned tongue, a member consisting of a cap having a circumferential rim, an open back and a face with

main and auxiliary openings, and a loose guard-plate occupying the interior of the cap at the open back and adapted to be subjected to the pressure of the tie and to transmit the 5 same to said tongue in its locking position and remove the tie from direct contact with said cross-bar, said parts being combined, forming an improved collar-button and neck-tie-fastener.

FREDERICK M. HASENFUS, JR.
